WINDOW

Torval J. Anderson, Chicago, Ill.

Application October 29, 1931. Serial No. 571,792

6 Claims. (Cl. 20—11)

This invention relates to improvements in window construction, comprising upper and lower sashes, and more particularly to the removable upper stiles of the frame.

5 An object of the invention is to provide a window frame with removable upper stiles, in order that it may be changed to any finished wood desired.

One object of the invention is to provide a window whereby the removable stiles and parting stops may be removed with the means for counter-balancing the sashes in operative position.

15 Another object is to provide a window frame which is more simple, better looking, and in which the weights, sash pulleys and cords are more conveniently accessible by removing the upper side stiles.

Another object is to provide a window frame with removable side stiles in order to extend the pockets higher in the frame to avoid any visible joints for the pockets in said stiles above the top of bottom sash.

One feature of the invention is to extend the sash pulleys into the pocket of the frame to provide access to the back side of said pulleys and to the inner ends of the sash cords on the back of said pulleys to simplify the proper adjustment of the sash cords by connecting the inner ends of the sash cords to the weights adjacent the lower ends of the pulleys after the other ends of said sash cords have been connected to the sash and the sashes lowered to rest on the sill of the frame.

35 The advantages of the invention will more fully appear as I proceed with the specifications

In the drawing:

Figure 1 is a front view of a window embodying my invention.

Figure 2 is a vertical sectional view showing the removable side stile in position.

Figure 3 is a horizontal sectional view taken on line 3-3 of Figure 1.

45 Figure 4 is a vertical sectional view with the removable side stile removed showing the pockets and means for counter-balancing the sashes in position in the well of the frame.

50 Figure 5 is a view of the removable side stile. Referring to the drawing in detail, the window frame comprises two even spaced side stiles 6 and upper removable side stiles 6a, a top lintel 7, a sill 8, and a stool 9. The side stiles 6, which are securely fastened, extend from the sill 8 to 55 the top of the lower sash when the lower sash

29 is in a closed position. The upper ends of the side stiles 6 are provided with rabbets adapted to receive one end of the removable side stile 6a, the other end of said removable stiles fits into a groove in the top lintel 7. To further support the removable side stiles 6a, the outer casings 10 and inner casings 11 are provided with rabbets into which the edge of the side stiles 6a are adapted to register. See Figures 1 and 3.

12—12a denote the longitudinal grooves in the side stiles 6—6a for the reception of the parting stops 13—13a respectively. Near the lower ends of the parting stops 13a is a screw 14 which serves to hold the removable side stiles 6a in place. The outer casing 15 on the opposed outer edges of the side stiles co-operate with the parting stops to form guide-ways or channels 16 for the upper sash 17. 18 designates the inner stops which co-operate with the parting stops to form guide-ways or channels 19 for the lower sash 20. In the sash channels 16—19 the side stiles 6 are provided with vertically opposed sash cord grooves 21 extending from the sill to the upper end of the side stiles. The upper removable side stiles 6a are made to co-operate with grooves 21 to provide free passages for the sash cords 22 on the back of the side stiles to the pulleys. See Figures 1-3.

The pulleys 23 are mounted on the top lintel 30 adjacent the back side of the upper side stiles 6a. The sash cords 22 or its equal are secured in suitable manner to the bottom rail of lower sash 20 and to the meeting rail of the upper sash 17.

It is noted that the means for counter-balancing the sashes are not connected to the removable side stiles in order that the whole section of the side stiles, extending from the top of the bottom sash to the lintel on the frame, and parting stops may be removed with said means left in operative position, and the pockets extended higher in the stiles, which makes the pulleys, sash cords and weights more conveniently accessible.

48
While I have herein shown and particularly described the preferred embodiment of my invention, it is to be understood that minor changes may be made in the details thereof without departing from the spirit and scope of 50 my invention as claimed.

I claim:

1. In a window frame construction, a lintel on said frame, sash pulleys mounted on said lintel sash cords mounted on said pulleys, side stiles 55

provided with sash cord grooves on said frame, pockets extending from the top of said side stiles to said lintel, removable side stiles adapted to cover said pockets, said removable side stiles provided with passages on the back side thereof and adjoining the top of said grooves to form continuous passages to said pulleys.

2. In a window frame construction, a lintel on said frame, upper and lower sash between the side stiles on said frame, sash pulleys, sash cords on said pulleys, one end of said sash cords connected to said sash, weights for counter-balancing said sash connected at the other end of said sash cords, a removable side stile extending from the top of said side stile to said lintel to provide a pocket to give access to said pulleys, weights and to said ends of said sash cords connected to said weights with said upper and lower sash lowered to the sill on the frame.

3. In a window frame construction, a lintel on said frame, upper and lower sash between the side stiles on said frame, sash pulleys mounted on said lintel in the well of said frame, sash cords on said pulleys, one end of said sash cords connected to said sash, weights for counter-balancing said sash connected at the other end of said sash cords, a removable side stile (provided with a parting stop) extending from the top of said side stile above said sash cords on said pulleys to said lintel, to provide a pocket to give access to said pulleys, weights and to said ends of said sash cords connected to said weights,

for the adjustment of said sash cords on said weights, with said sash lowered to the sill on the frame.

4. In a window frame construction, a lintel on said frame, side stiles, a pocket in said frame above said side stiles, a removable side stile extending from the top of said side stile (flush with the face side) over said pockets to said lintel to provide a plane unbroken surface on the face of said removable side stile to the top 10 of said frame.

5. In a window frame construction, a well in said frame, side stiles, a pocket to said well extending from said side stiles to the lintel on said frame, sash pulleys connected to said lintel in 15 said well and extending into said pocket, a removable side stile extending over said pulleys in said pocket to provide access to said pulleys.

6. In a window frame construction, a well in said frame, side stiles, a pocket to said well extending from said side stiles to the lintel on said frame, sash pulleys connected to said lintel in 20 said well and extending into said pocket, a removable side stile extending from the top of said side stile (flush with the face side) over said 25 pulleys in said pocket to said lintel to give access to said pulleys and to provide a plane unbroken surface on the face of said removable side stile from the top of said side stile to the lintel on said frame.
